UNITED STATES PATENT OFFICE

157,183

BUTTER SPREADER

George H. Newell, Racine, Wis.

Application May 8, 1948, Serial No. 146,251

Term of patent 14 years

(Cl. D44—29)

To all whom it may concern:

Be it known that I, George Newell, a citizen of the United States, residing at Racine, in the county of Racine and State of Wisconsin, have invented a new, original, and ornamental Design for a Butter Spreader, of which the following is a specification, reference being had to the accompanying drawing, forming part thereof.

Figure 1 is a perspective view of a butter spreader, showing my new design.

Figure 2 is a side elevational view.

Figure 3 is a top plan view.

Figure 4 is a front elevational view.

Figure 5 is a rear elevational view,

I claim:

The ornamental design for a butter spreader, as shown.

GEORGE H. NEWELL.
